UNITED STATES PATENT OFFICE.

VRL I. CILLEY, OF GRAND RAPIDS, MICHIGAN.

DESIGN FOR A TAIL-LIGHT FOR VEHICLES.

58,712.

Specification for Design.

Patented Aug. 30, 1921.

Application filed October 2, 1920. Serial No. 414,374. Term of patent 14 years.

To all whom it may concern:

Be it known that I, VRL I. CILLEY, a citizen of the United States, residing at Grand Rapids, in the county of Kent and State of Michigan, have invented a new, original, and ornamental Design for Automobile Tail-Lights, of which the following is a specification.

The one figure is a front elevation of a tail light showing my design in which A represents an ordinary tail light "bulls-eye" preferably showing red when illuminated from within the case D. To complete the design I make use of one or more openings

B at each side of the tail light A, preferably showing white when illuminated either from without, or from within the case, and of such form as may be desired.

The design is made to show through a transparent panel C in the case D.

What I claim as new, is:

The ornamental design for a tail light for vehicles, substantially as shown and described.

Signed at Grand Rapids, Michigan, September 28, 1920.

VRL I. CILLEY.
